Patented Apr. 26, 1921.

FIG. 2.

John T. Huddle,
By Neelorenborn,
Attorney

UNITED STATES PATENT OFFICE.

JOHN T. HUDDLE, OF WASHINGTON, DISTRICT OF COLUMBIA.

COMBINATION DUPLICATE OR SINGLE CANE OR STICK.

1,375,912.

Specification of Letters Patent.

Patented Apr. 26, 1921.

Application filed March 10, 1921. Serial No. 451,419.

To all whom it may concern:

Be it known that I, JOHN T. HUDDLE, a citizen of the United States, residing at Washington, in the District of Columbia, 5 have invented certain new and useful Improvements in Combination Duplicate or Single Canes or Sticks, of which the following is a specification.

This invention relates to a cane or stick 10 which is capable of being converted into two sticks or canes, or a cane, and a stick having attached thereto an umbrella, and each of said canes or sticks or cane and umbrella being provided with a handle for 15 gripping the same to firmly support a part of the weight of the user.

The object of the invention is to provide a cane or stick of the character above indicated which is particularly adapted for use 20 by invalids, infirm persons or cripples, and can be used as a single cane or stick, or easily and quickly converted into two canes or sticks if desired and found necessary to properly support or assist a person to walk 25 or move about.

A further object of the invention is to provide a combination cane or stick of the nature referred to which will have a minimum of weight and consist of the least number 30 of parts, cheaply manufactured, easily assembled, and quickly converted into two canes or sticks without the use of any special tool or machinery processes, and none of the parts of said combination stick requiring 35 any screws, bolts or other fastening means for securing them together and which are liable to be misplaced or lost.

Other objects and advantages of the invention will appear from the detailed description to be hereinafter given.

The invention consists of structural characteristics and relative arrangements of elements which will be hereinafter more fully described and particularly pointed out in 45 the appended claims.

In the one sheet of drawings in which similar reference characters indicate the same parts in the several figures,

Figure 1 is a longitudinal section of one 50 form of the invention when in use as a single cane;

Fig. 2 is an enlarged and fragmentary sectional view of the handle or gripping section of the cane shown in Fig. 1;

Fig. 3 is a view similar to Fig. 2, of a modified form;

Fig. 4 is a sectional view taken on line IV—IV of Fig. 3, and

Fig. 5 is a view similar to Fig. 1, showing the inner stick as an umbrella.

Referring to Figs. 1 and 2 of the drawings, 10 is an inner straight stick having preferably integrally connected therewith the circular curved grip or handle section 11. 12 is the hollow and outer straight stick 65 section having an internally threaded upper end 13 and a lower closed ferrule end 14, and is preferably so proportioned and arranged as to snugly fit about the straight portion 10 of the inner stick as shown in Fig. 1. A 70 hollow handle 15 is provided having a curvature of such shape and diameter of bore as to adapt the same to easily and readily slip over the curved grip or handle section 11 of the inner stick, said hollow handle 15 75 at its open end having an externally threaded section 16 adapted to engage as shown the internally threaded section 13. A small cushion spring 17 is inserted within and at the ferrule end of the hollow outer stick 80 section 12 for the purpose of preventing the inner stick 10 from rattling.

In Fig. 3, the same invention is shown as disclosed with respect to Figs. 1 and 2, except that the upper end of the outer hollow 85 stick 121 is provided with an externally threaded section 131, which is engaged by an internally threaded sleeve 161 rotatably carried or supported by the flange 18 on the open end of the hollow curved handle 90 151.

Fig. 5 shows the same invention as disclosed in Figs. 1 and 3, except that the straight section 101 of the inner stick is provided with a collapsible umbrella 102 95 adapted to be fitted and slid into the hollow outer stick 12 as shown, said stick 12 adapted to act as a cover and carrier for the umbrella.

The operation of the invention is as follows:

The parts being arranged as shown in Figs. 1 and 2, which show the invention when used as a single cane or stick, if it is desired to convert the same into two sticks 105 or canes, all that is necessary is to unscrew the threaded end 16 of the hollow handle 15 from engagement with the threaded end 13 of the hollow or outer stick section 12, by gripping the section 12 with one hand to 110 prevent it from rotating, and properly turn with the other hand the hollow handle 15

and rotating with it the inner handle 11 with its straight section 10, until the threaded sections 13 and 16 are disengaged, when the inner stick 10, and gripping end 5 11 with the hollow handle 15 attached to and covering the same, can be removed from the outer hollow section 12. After the foregoing operations, the hollow handle 15, can be readily and easily slipped off the inner 10 grip section 11 by gripping the handle 15 with one hand and the stick 10 with the other hand and pulling or pushing the outer or closed end of the handle 15 toward the stick 10, when the handle will slip off the grip 15 section 11, for the reason that the curvatures of the bore of handle 15 and grip 11 are on the same radius of circular arc. The 20 detached hollow handle 15 can now be independently screwed or firmly secured to the end of hollow stick 12 by oppositely rotating handle 15, so that its threaded end 16 again engages the threaded end 13 of outer stick 12, but without the inner stick 10 being within the hollow or outer section 25 12. Thus it will be seen that two sticks, firm in construction, are now provided, each of which is formed with a strong and rigid handle to be gripped by any one who desires to use or requires the assistance of two 30 canes.

If it is desired to restore the inner cane or stick 10 within the hollow outer section 12, the foregoing operations are simply reversed and need no further explanation.

35 The principle of assembling or disassembling the form shown in Figs. 3 and 4, is substantially the same as just explained, except in this modification it is not required to turn the handle 151, but all that 40 is necessary is to turn the sleeve 161 in the proper direction to be disengaged from the threaded section 131, as will be readily understood.

From the foregoing disclosure of the 45 construction, arrangement and relation of the parts and mode of using the same, it will be seen that all the objects and advantages recited in the statement of invention have been fully and efficiently carried out, and 50 while I have shown and described the pre-

ferred form of my invention, many changes or modifications will readily suggest themselves to any one without departing from the essential features of the present improvements and be within the scope of the 55 claims.

What I claim is:

1. A combination duplicate or single cane or stick comprising an inner stick having a straight section and a curved gripping end 60 formed in the arc of a circle, an outer hollow straight stick adapted to surround and receive the straight section of the inner stick, a curved hollow handle having a bore of the same curvature as the curved gripping end 65 of the inner stick and adapted to slip over said curved gripping end, and means for connecting one end of the hollow handle with one end of the outer hollow stick.

2. A combination duplicate or single cane 70 or stick comprising an inner stick having a straight section and a curved gripping end formed in the arc of a circle, an outer hollow straight stick adapted to surround and receive the straight section of the inner 75 stick, a curved hollow handle having a bore of the same curvature, diameter and length as the curved gripping end of the inner stick and adapted to slip over and snugly surround said curved gripping end, and 80 means for connecting one end of the hollow handle with one end of the outer hollow stick.

3. A combination duplicate or single cane 85 or stick comprising an inner stick having a straight section provided with an umbrella, and a curved gripping end formed in the arc of a circle, an outer hollow straight stick adapted to surround and receive the straight section with umbrella of the inner 90 stick, a curved hollow handle having a bore of the same curvature as the curved gripping end of the inner stick and adapted to slip over said curved gripping end, and 95 means for connecting one end of the hollow handle with one end of the outer hollow stick.

In testimony whereof I affix my signature.

JOHN T. HUDDLE.
